UNITED STATES PATENT OFFICE.

JOHN C. DUEBER, OF CANTON, OHIO.

DESIGN FOR A WATCH-MOVEMENT PLATE.

SPECIFICATION forming part of Design No. 28,319, dated March 1, 1898.

Application filed September 1, 1897. Serial No. 650,307. Term of patent 7 years.

to all whom it may concern:

Be it known that I, JOHN C. DUEBER, a citizen of the United States, and a resident of Canton, county of Stark, State of Ohio, have invented a new and original Design for a Watch-Movement Plate, of which the following is a full, clear, and exact description, reference being had to the accompanying drawing, making part of this specification.

The invention relates to a new design for watch-movement plates; and it consists of a design of the configuration and ornamentation shown in the accompanying drawing, in which I have illustrated my invention in a top plan view.

The leading features of my design consist of the top plate A, the barrel-bridge B, and the balance-cock C, damasked with a series of burnished circles having the appearance of concave grooves or corrugations. The grooves or corrugations of the top plate A commence at the center of the plate and cover the entire surface of the plate, each circle being formed from the same center or pivot, but each succeeding circle being of a greater

diameter. The balance-cock C is burnished in the same manner, and the circles thereon conform in center and diameter to those upon the top plate.

Upon the barrel-bridge B the burnished circles commence at both ends and run across the plate from top to bottom, meeting at a point above the center of the plate, as shown. The circles may have either the appearance of being concave or convex and may be of any desired width, the object being when the movement is completed and the balance-wheel and spring are in motion to produce a pleasing and desirable effect of scintillation, giving the appearance of motion to all parts of the plate.

What I claim is—

The design for a watch-movement plate, as herein shown and described.

In testimony whereof I have hereunto set my hand this 13th day of August, A. D. 1897.

JOHN C. DUEBER.
